UNITED STATES PATENT OFFICE.

ERNEST J. SIPES, OF FALKNER, MISSISSIPPI.

DESIGN FOR A WATCH FOB.

Application filed November 10, 1924. Serial No. 11,348. Term of patent 7 years.

To all whom it may concern:

Be it known that I, ERNEST J. SIPES, a citizen of the United States, residing at Falkner, in the county of Tippah and State of Mississippi, have invented a new, original, and ornamental Design for a Watch Fob, of which the following is a specification, reference being had to the accompanying drawing, forming part thereof, in which the figure is an elevational view of my design for watch fob.

I claim:

The ornamental design for a watch fob, as shown.

ERNEST J. SIPES.

Witnesses:

WILLIE SIPES,
NOAH SIPES.
